DESIGN FOR A PENDANT BROOCH OR SIMILAR ARTICLE

Michael Chernow, Brooklyn, N. Y.

Application February 5, 1936, Serial No. 60,987

Term of patent 7 years

To all whom it may concern:

Be it known that I, Michael Chernow, a citizen of the United States and residing at Brooklyn, in the County of Kings and State of New York, have invented a new, original, and ornamental Design for a Pendant Brooch or Similar Article, of which the following is a specification, reference being had to the accompanying drawing, forming part thereof, and in which

Fig. 1 is a plan view of the pendant brooch or similar article.

Fig. 2 is a side elevation of one of the character units thereof.

The characteristic features of my design reside in the plurality of initial bearing units separately and pendently linked; the initials shown in each unit being merely illustrative.

I claim:

The ornamental design for a pendant brooch or similar article substantially as shown and described.

MICHAEL CHERNOW.
